UNITED STATES PATENT OFFICE.

GUSTAV GAERTNER, OF VIENNA, AUSTRIA, ASSIGNOR OF ONE-HALF TO THE FIRM:
JOH. KREMENEZKY, OF VIENNA, AUSTRIA.

APPARATUS FOR PREVENTING DISTURBANCES OF THE STATE OF HEALTH DUE TO
SEESAW AND ROTARY MOTIONS.

Application filed May 9, 1927, Serial No. 189,998, and in Austria July 29, 1926.

When the static organ is exposed to see saw and rotary motion, disturbances of the state of health are caused which manifest themselves in the first place by giddiness, 5 vomiting, salivation, headache and the like. These disturbances are most felt in sea and air travels.

The subject matter of the present invention is an apparatus which permits to prevent 10 these disturbances. The apparatus is more particularly distinguished by great simplicity and ready portability, so that any person can carry it with him or her at all times during a travel on the sea or in the 15 air and may use it at will without his or her other occupation being interfered with.

According to the invention the static organ is exposed during the see saw or rotary motion to a weak electric current entering 20 near the static organ, that is to say, the anode of an electric circuit is applied near the static organ. The cathode of this circuit is preferably applied to the forehead or to the neck or to the breast, that is to say 25 preferably in the line of symmetry of the body. As a source of electricity, for instance a dry battery of a voltage of about four volts is sufficient. The intensity of current thus set up is about 2 to 3 milliamperes, and therefore the battery may suffice 30 for days.

It has been found that the disturbances due to see saw or rotary motions are suppressed completely or to the major part 35 when an anode is applied to each of the two mastoid processes. It is essential that through both static organs a current of practically the same intensity should pass as otherwise disturbances of equilibrium may 40 readily occur.

Fig. 1 of the drawing shows the apparatus in position on a patient's head. Fig. 2 is a plan view showing battery connections.

The apparatus is preferably constructed 45 of a frame 1 resembling a head telephone, the two anodes 2, 3, being mounted in such a manner that on putting on the frame in the usual manner, the two anodes come into contact with the mastoid processes under a slight pressure, see Fig. 1. Preferably on 50 the frame 1 a strap 4 is arranged which car-

ries the cathode 5 in such a manner that this cathode bears with slight pressure against the forehead or the neck. The connection with the source of current is preferably such 55 that any mistake as regards the poles is excluded. For this purpose advantageously a plug contact is used which does not permit of any mistake as regards the poles.

The cathode 5 may be placed on any other 60 part of the body, for instance on the arm and therefore the bearing point of the cathode may be readily changed whenever the continued application to the forehead or the neck causes any inconvenience. 65

The current intensity of 2 to 3 milliamperes being so small that it can be endured without any obnoxious bye effects for hours and days, as has been found by special experiments, the use of any control device may 70 be dispensed with which in turn results in that the weight of the apparatus may be very small, any person may carry it with him or her at all times and that it may be mounted ready for use or dismounted with 75 in a few seconds.

In order to keep the electrodes slightly moist for a longer period of time, the sponge attached to the electrode in the usual way is 80 preferably made slightly greater so that it also covers the back of the electrode. If the part of the sponge pressed against the body by the electrode with a slight pressure becomes dry it is only necessary to squeeze the 85 sponge at one or more points. Thereby the liquid contained in the sponge at these points is forced into the part of the sponge already dried.

What I claim is:

1. In apparatus for preventing mal de 90 mer and dizziness from rotational motions and the like, a headset including a resilient frame, electrodes of similar polarity carried at the opposite sides thereof adapted to press against the sides of the head, and a third 95 electrode of opposite polarity in circuit with the first-named electrodes, and with an electrical source, said third electrode being adapted also to make contact with some part of the body.

2. In apparatus for preventing mal de 100 mer and dizziness from rotational motion

- and the like, a headset including a resilient frame having a transverse part, electrodes of similar polarity carried by said part at opposite sides thereof adapted to press against the sides of the head, said frame having a portion extending angularly of said transverse part, and an electrode of opposite

polarity carried by said angularly extending portion and adapted to press against a part of the head, and an electrical source with 10 which said electrodes are in circuit.

In testimony whereof I affix my signature.

GUSTAV GAERTNER.
